VERTICAL UNWIND DEVICE

Charles A. Dickhaut, New Brunswick, and Sterling A. Warner, Somerville, N. J., assignors to John Waldron Corporation, New Brunswick, N. J., a corporation of New Jersey

Application March 4, 1936, Serial No. 67,012

7 Claims. (Cl. 242—76)

This invention relates to a vertical winding or unwinding device.

In connection with the manufacture or use of web materials it is sometimes requisite that the web of material is wound or unwound in the vertical plane. An illustration is in the vertical coating of a web of paper and its subsequent drying on edge. It has heretofore been customary to utilize horizontal winding or unwinding mechanisms and to turn the web into the vertical plane by angle bars or other turning means. Such method requires additional space, additional mechanisms and there is always present the difficulty of maintaining the web at a uniform elevation due to the natural tendency caused by gravity of the web to drop. To overcome the dropping of the web it is necessary to maintain the web as taut as possible, which in the case of paper, causes breakage and consequent waste.

One of the objects of this invention is to provide a vertical windup or unwind mechanism for handling webs of paper fabric and the like.

Still another object of this invention is to provide a vertical windup or unwind device wherein the web of paper will be automatically maintained at a constant elevation.

Still another object of the invention is to provide a vertical windup or unwind mechanism of simplified construction wherein the rolls may be secured to prevent the necessity of shutting down the machine performing operations on a web.

Still another object of the invention is to provide a floating or pneumatically supporting windup or unwind mechanism automatically controlled to maintain the rolls at a predetermined elevation.

Referring to the drawings:

Figure 1 is a view in elevation of a device embodying the principles of our invention.

Figure 2 is a top plan view of Figure 1.

Figure 3 is a view of Figure 1 along the line 3, 3, looking in the direction of the arrows.

Figure 4 is a plan view of the pneumatic diaphragm supporting the mechanism.

Figure 5 is a cross sectional view along the line 5, 5, looking in the direction of the arrows.

Fig. 6 is a section on the line 6—6 of Fig. 1.

In carrying out our invention, we provide a frame 1 composed of channel irons and angle irons. Centrally of frame 1 is a shaft 2 that is journaled in the frame 1 at the top and bottom and extends above and below the cross pieces 1' of frame 1. The upper portion of shaft 2 is threaded for a spring retaining nut 3. A spring

4 is secured on shaft 2 between nut 3 and frame 1. Shaft 2 has a yoke or cross arm 5 secured thereto adjacent the top cross pieces 1' and another yoke or cross arm 6 adjacent the bottom of cross pieces 1'. Cross arms 5 and 6 are rotatable with shaft 2. Cross arm or yoke 5 has bearings 7, 7', to receive the roll spindles or axles 8'. The bearings are split bearings, one-half of which are secured in the ends of yoke 5 and the other half on quick release levers 9, 9'. The quick release levers have compression springs 10, 10', and latches 11, 11'. The bottoms of spindles 8, 8', are journaled in bearings 12, 12', with friction brakes 13, 13', to retard spindles 8, 8', to maintain the web when being unwound in proper tension. The friction brakes are adjustable by means of wing nuts 14, 14'. An adjustment wheel 15 has a hub 15' which is interiorly threaded at 15² for co-operation with threads 15³ provided on the shaft 2. Rotation of the wheel 15 brings the lower end of the hub 15' into engagement with the cross-piece 1' and further rotation of the wheel will effect elevation of the shaft 2. Thus in the event of failure of the air pressure, the shaft 2 may be adjusted vertically by manual rotation of the wheel 15.

Shaft 2 rests directly on button 16 of diaphragm supporting surface 17 which in turn rests on diaphragm 18 with under supporting surface 19. Diaphragm supporting mechanism 20 raises or lowers shaft 2 automatically with a variation of the elevation of the upper edge of the web. Pneumatic pressure is delivered through pipe 21 to diaphragm mechanism 20 and pipe 22 being connected with pipe 21 carries the same pressure to valve 23 which is operated by finger 24 resting on the edge of web 25. As the finger 24 moves up or down, it opens or closes valve 23 thereby changing the pressure in pneumatic mechanism 20. Valve 23 is arranged to generally permit some escape of pressure in order to have a sufficient leeway to take care of maximum requirements. It is obvious that the finger 24 may operate a suction pneumatic adjustment or a pressure pneumatic adjustment. The pneumatic control is practically instantaneous and maintains the elevation very accurately. Upon the unwinding of one roll, the other roll is turned into position by the rotation of handle 26 which carries sprocket wheel 27, rotating chain 28, which in turn rotates sprocket 29 on shaft 30. Shaft 30 carries worm 31 meshing with worm gear 32 on shaft 2. Gear 32 rotates shaft 2 for spindle 8' to take the position of spindle 8. Spindle 8 is then removed by releasing release

40

45

mechanism 9 and the removal of spindle 8 from the bearing 12 and brake 13. A new roll is then inserted and the release lever is returned to its locked position. The removal of the old spindle 5 and the replacement by a new roll and spindle can be accomplished while the roll already inserted is in process of unwinding or of being wound up.

Although the device is shown as an unwinding mechanism, it is also adapted as a windup mechanism. A pulley secured to spindle 8 with a release of brake 13, permits its immediate adaptation. Any other well known form of drive of the spindle may be used.

15 Shaft 2 between nut 3 and gear 32 has a spring 4 to relieve the weight of the mechanism from pneumatic mechanism 20. Spring 4 is preferably designed to support the fixed load other than the weight of the web of material being 20 unwound.

Various details may be made and still fall within the scope of our invention.

It will thus be seen that we have invented an unwind or windup mechanism for winding or unwinding a web of material in the vertical plane and automatically maintaining the web at a predetermined elevation by supporting the mechanism pneumatically and regulating the pneumatic control of the supporting means by the 30 elevation of the edge of the web.

What we claim is:

1. In an unwind mechanism, a frame, a shaft journaled in said frame, arms journaled on said shaft, spindles for rolls of material rotatable in 35 said arms, a pneumatic diaphragm to support the end of said shaft, and means for pneumatically moving said diaphragm to change the elevation of said shaft.

2. In an unwind mechanism, a frame, a shaft 40 journaled in said frame, arms journaled on said shaft, spindles for rolls of material rotatable in said arms, a pneumatic diaphragm to support the end of said shaft, means for pneumatically moving said diaphragm to change the elevation of said shaft, said means pneumatically controlled by a valve operated by a finger resting upon the material being unwound.

3. In an unwind mechanism, a frame, a shaft 45 journaled in said frame, arms carried by said shaft, spindles for rolls of material rotatable in said arms, a spring for supporting said shaft, pneumatic means for automatically varying the elevation of said shaft, said pneumatic means

having control means effected by variation in the height of the edge of the web of material unwound from the roll of material.

4. In an unwind mechanism, a frame, a shaft 5 journaled in said frame, arms carried by said shaft, split bearings in said arms, quick release latches for said bearings, spindles for rolls of material rotatable in said bearings, means for manually adjusting the elevation of said shaft means for automatically and pneumatically varying 10 the elevation of said shaft, said pneumatic means operable upon variation of the height of the edge of the web being unwound from one of said spindles.

5. In an unwind mechanism, a frame, a shaft 15 journaled in said frame, arms carried by said shaft, a spring for supporting the weight of said shaft and arms, split bearings in said arms, quick release latches for said bearings, spindles for rolls of material rotatable in said bearings, 20 means for manually adjusting the elevation of said shaft, and means for rotating said shaft to transpose said spindles when a roll is unwound to permit the unwinding of the second roll of material and the insertion of a third spindle 25 and roll of material thereon in place of the unwound first spindle.

6. In an unwind mechanism, a frame, a shaft 30 journaled in said frame, members carried by said shaft, a spring for supporting the weight of said shaft and members, spindles for rolls of material rotatable in said supporting members, means for manually adjusting the elevation of said shaft, friction brakes carried by said members 35 and acting on said spindles, and means for rotating said shaft to transpose the position of said spindles.

7. In an unwind mechanism, a frame, a shaft 40 journaled in said frame, members carried by said shaft, a spring for supporting the weight of 45 said shaft and members, spindles for rolls of material rotatable in said supporting members, means for manually adjusting the elevation of said shaft, friction brakes carried by said members and acting on said spindles, means for rotating said shaft to transpose the position of said spindles, and pneumatic means for varying the elevation of said shaft to maintain the elevation of the web of material being unwound at the same elevation during the unwinding. 50
